UNITED STATES PATENT OFFICE.

JOHN L. LATTA, OF HICKORY, NORTH CAROLINA.

PNEUMATIC PUMP.

Application filed October 13, 1922. Serial No. 594,282.

To all whom it may concern:

Be it known that I, JOHN L. LATTA, a citizen of the United States, residing at Hickory, in the county of Catawba and 5 State of North Carolina, have invented certain new and useful Improvements in Pneumatic Pumps, of which the following is a specification.

This invention relates to pneumatic 10 placement pumps, and more particularly to pumps for use in connection with so called "fresh water systems" of water supply, in which water is delivered directly from a well or other natural reservoir, to the supply 15 faucet, without the intervention of any storage tank. In such systems, the pump is submerged in the water in the well and is connected to a source of compressed air in such a way that the opening of a faucet 20 causes the pump to operate and deliver water under pressure.

Pumps and pumping systems of this general nature are already well known and have been used with more or less success. Such 25 prior pumps have, however, involved certain structural difficulties, and been subject to certain defects of operation, such, for example, as the leakage or blowing over of the compressed air.

30 The present invention relates generally to that type of pump covered by my prior Patent, Number 1,237,530, dated August 21, 1917, comprising a single cylinder or pump chamber, which is alternately filled with 35 water and subjected to air pressure for expelling the water. The alternate feeding of compressed air to the pump chamber and its exhaust therefrom is produced by valve mechanism controlled directly or indirectly 40 by the varying level of the water in the chamber, as it is filled and emptied. In my above mentioned patent, as well as in all other structures heretofore proposed, so far as I am aware, this valve mechanism, and 45 the controlling and actuating devices therefor were distributed at various points throughout the interior of the pump chamber, so that, in order to gain access to these parts, for repair or replacement, it was necessary to separate and dismantle the entire 50 pump.

One of the primary objects of the present invention is, therefore, to provide a pump structure of the general character above mentioned, in which all operative parts of 55 every kind, whatsoever, are mounted upon

or carried by the head member which closes the upper end of the pump chamber or cylinder, so that the entire mechanism is removable from the cylinder with the head member. Furthermore, I propose to provide the head member with a removable upper section or cap, so that, when this cap is taken off, all removable operating and controlling elements, such as valves, floats, etc., 60 can be withdrawn and removed upwardly from the head member, without separating the head member from the cylinder body. Thus, access may be had to any of the parts, 65 for inspection, replacement or repair, without the necessity for exposing the interior of the pump chamber at all.

A further object of the invention is to provide an improved exhaust valve operating motor and improved means for controlling the same, such means comprising a pipe 70 extending downwardly in the pump chamber and terminating at a point above the lower end of the water discharge pipe, whereby a water seal is always maintained 75 around the water discharge pipe, and the entrance of air into this pipe made possible.

A still further object of the invention is to provide an improved construction of 80 water inlet or check valve at the lower end of the pump chamber or cylinder, such valve being so constructed that the parts subject to wear may be removed and replaced from the outside, without the necessity for obtaining access to the interior of the cylinder. 85 Thus, the working parts of this check valve may be replaced, without in any way dismantling the pump itself.

Water found in wells in many parts of the 90 country, especially in deep wells, contains objectionable quantities of mineral matter and other foreign substances in solution, such as various compounds of iron or other 95 metals, ammonia, sulphuretted hydrogen and other gases. I find that many of these impurities can be either removed or rendered much less objectionable by aeration of the water. Another important object of the 100 invention, is therefore, to provide means for introducing the compressed air into the pump cylinder in such a way that it will pass through and thoroughly aerate the water contained therein, before such water 105 is expelled.

With the above and other objects in view, 110 and to improve generally upon the details

of construction and arrangement of such apparatus, my invention consists in the construction, combination and arrangement of parts hereinafter described and claimed, 5 and illustrated in the accompanying drawings, in which:

Fig. 1 is a vertical longitudinal section through my improved pump complete, parts being shown in elevation;

10 Fig. 2 is a plan view thereof;

Fig. 3 is a detail view on an enlarged scale, of one of the parts of the exhaust valve structure;

15 Fig. 4 is a plan view of the lower section of the head member, the upper section or cap being removed;

20 Fig. 5 is a plan view of the cage member, forming a part of my improved check valve structure, constituting the lower end of the pump cylinder.

Fig. 6 is a fragmentary sectional view, similar to Fig. 1, but showing the exhaust valve operating motor and associated parts, on a larger scale; and

25 Fig. 7 is a fragmentary sectional view showing the upper end of the float for controlling the exhaust valve operating motor, such view being similar to Fig. 1, but on an enlarged scale.

30 Referring to the drawings in detail, my improved pump comprises a cylinder or body 1, preferably formed of a piece of pipe or tubing, an upper or top head member 2 and a lower member 3 closing the bottom of the cylinder. This cylinder is, of course, placed vertically in the well and is entirely submerged in the water, as is usual.

35 The bottom or foot member 3 of the cylinder comprises a cage member 4, which is provided with an annular groove 4^a to receive the lower edge of the cylinder 1, suitable packing being placed in this groove, to insure a tight joint. To the bottom of the member 4 is secured a retaining ring or member 5, having a central preferably flared opening 5^a, constituting the water inlet. Held between the members 4 and 5, and received in grooves formed in said members, is a seat member 6, preferably formed of rubber or other soft material. This is in the shape of a flat disc having a central opening therethrough, registering with the opening in the member 5. The cage member 4 has a central bore or chamber 7, over which extends a suitable cage structure 8, the diameter of the chamber 7 being considerably larger than that of the central opening in the member 6, so that the inner portions of said member 6 constitute an annular seat on which rests a disc valve 9. This may be made of metal or of some hard molded material, such as bakelite.

40 The head member 2 comprises a lower section 11 and an upper section or cap 12,

the lower face of the section 11 being formed with an annular groove 11^a, adapted to receive the upper edge of the cylinder 1, such groove preferably containing suitable packing so as to produce a tight joint. The cylinder body and the head and foot members are held together in assembled relation, as shown, by means of tie rods 10, any suitable number of which may be employed, and which are located inside the cylinder. 75 These tie rods pass through the members 4 and 5, and are provided at their lower ends with nuts 10^a, which bear against the lower face of the member 5. By removing these nuts, it is apparent that the retaining member 5 may be taken off, thus permitting replacement of the seat member 6, and valve member 9, when necessary, without separating the member 4 from the cylinder body 1. 80

85 The upper section 12 of the head member is secured to the lower section 11 thereof, by means of a series of machine screws 13, a suitable packing 14 of soft material being interposed between the two sections, so as to produce an air tight joint.

90 Screwed into or otherwise secured to the top of the upper section 12 of the head member, are three pipes 15, 16 and 17, the pipe 15 serving to supply compressed air or other motive fluid to the pump, the pipe 95 16 being the delivery pipe through which water discharged from the pump cylinder is conveyed to the house faucets, and 17 being the exhaust pipe for conducting the compressed air, escaping from the pump cylinder, up to a point above the water level in the well.

95 From the pipe 15 extends a passage 18 to a valve seat 20, located at the bottom of a bowl-shaped chamber 19, formed in the upper part of the upper section 12 of the head member. A ball valve 21 rests upon the seat 20, and is held to such seat against the pressure of the incoming motive fluid by means of a spring 25, this spring bearing at one end against the top of a cap 23, secured to the section 12, by means of screws 24, and being centered at the other end around a bolt 22^a, having a flattened head 22^b which bears upon the ball 21. The bolt 110 22^a is carried by a flexible diaphragm 22, extending across the top of the chamber 19, and having its edges interposed between the cap 23 and the section 12 of the head member. This valve 21, when seated, as shown in Fig. 1, does not entirely shut off the admission of compressed air, but permits a slight leakage, the construction and operation of this supply valve and its controlling means being substantially the same as that disclosed in my said prior Patent, Number 1,237,530. An air supply port or passage 26 extends from the chamber 19, down through the head member to the interior of the cylinder, such passage being formed 115 120 125 130

partly in the lower section 11, and partly in the upper section 12, the two parts being brought into registry when the sections are assembled. The packing 14 is, of course, cut 5 away, adjacent this, and the other passages and openings in the head member, in order to permit passage of fluid or access to the parts, as the case may be.

In the lower end of the passage 26 is secured 10 an air discharge pipe 76, which extends down to a point near the bottom of the cylinder. The lower end of this pipe is closed, as by means of a cap, and is provided with a plurality of small perforations 76^a, through which the air enters the cylinder.

Also, extending through the lower section 11 of the head member is a passage 27, in the lower end of which is secured a water discharge pipe 28, which extends downwardly into the cylinder, so that its lower open end 28^a is located adjacent the foot or check valve at the bottom of the cylinder. Formed in the upper section 12 of the head member, 25 immediately above the upper end of the passage 27, is a pocket or chamber 30, in which is confined a ball valve 29 which sits on the upper end of the passage 27 and thus acts as a check valve to prevent the return flow 30 water into the pump cylinder. From the chamber 30 extends a passage 31, which communicates with the delivery pipe 16.

Communicating with the exhaust pipe 17 is a passage 32, formed partly in each section 35 of the head member, and opening at its lower end into a relatively large bore or pocket 33, formed in the section 11 of the head member. At the lower end of this bore or pocket is a partition wall 34 having a central opening into which is screwed the upper end of a tubular valve cage 35. The lower end of this cage, which projects only a relatively short distance below the head member, is closed by means of a cap 36, having 45 an opening 36^a, through which water may escape from the cage. At a point near the middle of its length, this cage is provided with a series of holes or openings 37, establishing free communication between the interior of the cage and the interior of the pump cylinder, and in the cage is confined a valve member which comprises a floating or buoyant ball 38.

Fitted in the bottom of the bore or pocket 55 33 is a combined cylinder head and valve seat member 39, shown in detail in Fig. 3. By reference to this figure, it will be seen that this member has a tubular portion 40 which projects down into the cage 35 and is provided at its lower end with a valve seat 41, shaped to receive the ball valve 38, this ball valve and seats serving to control the exhaust of motive fluid from the pump chamber. It will be noted that the valve seat 41 is located 60 at a point in the cage 35, just above the

openings 37 therein, for a purpose hereinafter described. The member 39 further comprises a pair of annular flanges 42, 43, spaced apart by a tubular portion 44, in which are formed a series of holes or openings 45. Above the shoulder 43 is a projecting boss 46 having a restricted central opening therethrough which serves as a guide for the plunger of the exhaust valve operating motor now to be described.

The exhaust valve operating motor, above referred to, comprises a tube or cylinder 48, of such size as to snugly fit the bore or pocket 33, and the lower edge of this cylinder is received in a groove 47, (see Fig. 3), formed in the annular shoulder 43 of the head and seat member 39. Arranged to reciprocate in this cylinder with an air tight fit is a piston comprising a cup leather 49 held between a pair of plates 50 and a pair of clamping nuts 51 85 screwed onto the threaded upper end of a piston rod or plunger 52, which, as above mentioned, extends downwardly through the guide 46 and projects into the tubular portion 40 of the head and seat member 39. It 90 will be noted, however, that this plunger is considerably smaller than the inside diameter of such tubular portion, thereby providing a relatively large free space 53, around the plunger through which air may pass. 95 An extremely small bleed port or passage extends longitudinally through the upper end of the piston rod 52, such passage opening out through the upper end of the rod, as indicated at 54 in Fig. 6, and communicating 100 with the space below the piston by means of a port 55. As will hereinafter appear, the piston is actuated by air or other motive fluid, but in actual practice, it is found that more or less water may sometimes make its 105 way into the space above the piston, and this bleed passage, above described, is for the purpose of permitting this water to leak away and escape downwardly into the pump chamber.

Interposed between the lower face of the piston and the flange 43 of the head and seat member is a spring 56, which spring tends to maintain the piston in the position shown in the drawings and serves to return the piston to such position after it has been actuated by fluid pressure, as hereinafter described.

The upper end of the cylinder 48 is closed by means of a plate or disc 58 having a 120 groove 59 formed in its edge to receive the end of the cylinder. This plate is shaped so as to make as close a fit as possible with the interior walls of the bore 33, as indicated at 60, in Fig. 6, and, although the packing 14 is, of course, cut away above this plate, the edge of such packing is made to overlap the joint 60, as indicated at 61, so as to make a practically air tight seal.

The plate or disc 58 is provided with one 130

or more openings 63, extending therethrough, from top to bottom, and these openings establish communication between the interior of the motor cylinder above the piston, and 5 a motive fluid supply passage 64, formed in the upper section 12 of the head member.

By reference to Fig. 1, it will be seen that the head and seat member 39 rests in the bottom of the bore or pocket 33, a packing 10 ring 57 being interposed between the flange 42 thereof, and the bottom of the pocket. The cylinder 48 rests upon the head and seat member and the plate 58 rests upon the cylinder. A set screw 62 passes through 15 and is threaded in the upper section 12 of the main head member and bears at its lower end upon the plate 58. It will therefore be seen that by tightening down on this screw, the parts 39, 48 and 58 are held 20 firmly in assembled relation, and moreover, a perfectly air tight joint is formed under the flange 42 by the packing 57. Thus, when the ball valve 38 is in engagement with the seat 41, escape of motive fluid from the pump cylinder is prevented.

Communicating with the passage 64 is a nipple 65 screwed into the upper section 12 of the head member and projecting substantially below the lower face thereof, as 30 clearly shown in Fig. 7, the lower end of this nipple constituting a valve seat for controlling the supply of fluid under pressure to the exhaust valve operating motor. This nipple or valve seat is located at the 35 upper end of another bore or chamber 66, extending vertically through the lower section 11 of the head member. Secured to such section and depending therefrom so as to constitute a continuation of the chamber 40 66 is a tubular casing 67, closed at its bottom by a bushing 68. Screwed into this bushing 68 is the upper end of a drop pipe 69, the lower end of which extends downwardly to a point near the bottom of the main cylinder, as indicated at 69^a, but above 45 the lower end of the water discharge pipe 28.

The casing 67 and bore 66 together constitute a chamber or water box, in which is confined a floating or buoyant billet 70. This billet or float may be of almost any 50 shape and construction, but is shown as comprising a cylindrical block of light wood or cork 71, incased in a surface coating or layer 72 of rubber. This rubber layer is 55 preferably made comparatively thick at the end of the billet, as shown at 73, in Fig. 7, so as to constitute a soft valve member for engagement with the seat at the end of the nipple 65. Moreover, an annular axially 60 projecting flange 74 is formed around the cushion 73, so as to provide a central basin or cup 75, so positioned that it will catch and retain liquid, and thus provide a water seal around the lower end of the nipple 65. 65 This water seal absolutely prevents en-

trance of air into the passage 64, even though the cushion 73 should not fit with entire accuracy.

Although there is no useful purpose served in having the above described flange 70 74 and valve cushion 73 at the lower end of the billet 70, still I prefer to make both ends of the billet alike, so that it is immaterial in which position it is placed, and also, so that if one end becomes worn, it can be reversed, and thus provide a new valve surface. It will, of course, be understood that the billet 70 is substantially smaller than the chamber 66, both in diameter and length, so that it may play freely therein, 80 and it will be seen that this billet constitutes a float controlled valve for governing the supply of motive fluid to the exhaust valve operating motor and therefor, indirectly, for governing the exhaust valve. 85

The operation of my improved pump will now be briefly described. As to accessibility of the parts, it will be noted that when the upper section 12 of the head member is removed, all operating and control elements can be withdrawn from the lower section 11, by which they are carried. Removal of the upper section 12 immediately exposes the check valve 29 and also affords access to the top of the exhaust valve operating motor. This motor can then be lifted out from the pocket in which it is mounted, and after the head and seat member 39 has been removed, the exhaust valve 38 itself may be reached and withdrawn by means 90 of a suitable tool. Also, the billet 70 can be lifted out of the chamber 66. Thus, it is possible to repair or replace any working 95 part of the pump without taking the lower section of the head member off of the cylinder. 100

Assuming the pump to be submerged in water, and the exhaust valve to have been just opened, as shown in Fig. 1, water will 110 flow into the cylinder by gravity entering through the check valve 9 at the bottom thereof, and will gradually fill the interior of the cylinder. As the water rises in the cylinder, it will also rise in the control or drop pipe 69, finally entering the casing 67 and tending to lift the float 70, so as to bring the valve surface carried thereby into engagement with the valve seat or nipple 65. As the water level reaches the upper 115 end of the pump cylinder, it will enter the cage 35 through the hole 36 in the bottom thereof, and will cause the buoyant exhaust valve 38 therein to float up into engagement with its seat 41. As soon as the exhaust valve is thus closed, pressure will immediately begin to build up in the upper end of the pump cylinder, due to slight leakage of compressed air past the inlet valve 21 and through the passage 26, and pipe 76. 120 This accumulating pressure on the surface 125 130

of the water in the cylinder will at once force the water up into the water box or float chamber 66, 67, to a level higher than that in the cylinder itself, and thus the floating billet 70 is forced into firm engagement with the nipple 65, if by any chance, it had not already come into engagement therewith. Thus, I have provided pressure controlled float operated means for closing the 10 pilot valve controlling the flow of fluid through passage 64.

A moment after the seating of the billet 70, against the nipple 65 occurs, pressure accumulates in the chamber 19 to such an 15 extent as to raise the diaphragm 22 against the tension of the spring 25, thus permitting the ball 21 to be lifted from its seat by the compressed air. The compressed air or other motive fluid thereupon rushes through the 20 passage 26 and pipe 76, into the pump chamber and expels the water therefrom, forcing it upwardly through the discharge pipe 28, passage 27, past check valve 29 and out through the passage 31 and delivery pipe 16.

It will be noted that the lower end of the 25 pipe 76 is submerged, and that the compressed air entering the pump chamber as above described issues from the small holes 76^a in the form of fine jets, which mingle 30 with the water thus thoroughly aerating the same.

As the water level falls in the pump cylinder, it does not fall in the water box or chamber 66, 67, for the reason that this chamber 35 or water box has been sealed at its upper end by the engagement of the billet 70 with the nipple 65, such seal being maintained absolutely tight by reason of the cup 75, as above explained. Therefore, the chamber 40 66 and casing 67 remain full of water, and a water column is maintained in this chamber and in the control pipe 69, during the entire time that the water is being expelled from the pump cylinder. Finally, when the 45 water level has been lowered to such a point as indicated by the line α — α in Fig. 1, the water seal at the lower end 69^a of the drop pipe 69 is broken, thus permitting the water to escape from such pipe and from the float 50 chamber 66, 67. The escape of water from the float chamber permits the float to fall to its lowermost position, as shown in Fig. 1, thus opening the end of the nipple 65. Thereupon, the compressed air or other motive 55 fluid which is in the pump chamber, and which has just expelled the water therefrom, enters the lower end 69^a of the control pipe and flows upwardly past and around the billet 70, through the nipple 65 and passage 60 64, to the exhaust valve operating motor, entering the cylinder of this motor above the piston through the ports 63 and causing the piston and plunger 52 to descend. The end of the plunger 52 engages the exhaust valve 65 68 and pushes it from its seat. In fact, the

plunger strikes this exhaust valve a sharp blow and suddenly dislodges it from its seat, projecting it to the bottom of the cage 35, as shown in Fig. 1. The confined motive fluid then escapes from the pump chamber 70 through the openings 37, up through the space 53 around the plunger, through the ports or openings 45 and thence into the exhaust passage 32 and pipe 17. It will be noted that this exhaust air enters the cage 75 35 through the openings 37 at a point between the valve seat 41 and the position which the ball 38 occupies at the bottom of the cage when the exhaust begins, and the inrush of air through these ports 37, at a 80 point above the bottom of the cage, serves to maintain the ball valve 38 away from the seat 41 and prevent it from being sucked back to the seat, as might otherwise occur.

It will be also observed that immediately 85 that exhaust valve 38 is unseated, the pressure on the upper side of the motor piston 49 is relieved, such release occurring through the port 64 and down through the pipe 69. Moreover, the pressure above the piston 90 would, in any event, quickly leak away through the bleed passage 54, 55. In any event, as soon as the main exhaust valve is opened, the spring 56 returns the piston to its normal position and retracts the plunger 95 52 from the cage so that the valve 38 may again be floated to its seat.

Owing to the fact that the water discharge pipe 28 extends below the lower end of the control pipe 69, it will be seen that the exhaust valve is also opened by the breaking of the seal at the lower end of the control pipe, while the water level is still above the lower end of the discharge pipe, thus making it impossible for "blow overs" to occur, or 100 for air to enter the water discharge pipe.

The issuance of air under strong pressure from the small submerged openings 76^a at the bottom of the pipe 76 in the form of fine jets, when the valve 21 opens, subjects the 105 water in the cylinder to violent agitation, and, in fact, blows it almost into a fine mist, thus producing complete aeration. At the same time, the water becomes thoroughly mixed and impregnated with minute particles of air, as is evidenced by its white, milky appearance. This aeration results in largely removing the objectionable gases carried by the water, which gases later pass out at the exhaust, and also serves to oxidize 110 many of the mineral substances held in solution, such as iron compounds, thus converting them into insoluble bodies. These insoluble bodies may then be precipitated or filtered out, or, if allowed to remain in the 115 water, are, on account of their inertness, much less objectionable, so far as taste and "hardness" are concerned, than the original compounds from which they were formed. In other words, this aeration, as above de- 120 125 130

scribed, greatly improves the quality of the water.

It will thus be seen that I have provided a single cylinder pneumatic displacement pump of exceedingly simple construction, in which the exhaust valve operating motor and the float controlled pilot valve therefor are both carried entirely by the cylinder head, from which cylinder head all operative parts 10 may be readily removed, for repair or replacement, and in which the incoming air is forced to travel through the water, so as to thoroughly aerate and purify the same, and it is thought that the many advantages of 15 my improved construction will be readily appreciated without further discussion.

What I claim is:

1. A pneumatic pump comprising a vertical cylinder, a head member therefor comprising upper and lower separable sections, and provided with ports for the inlet and exhaust of motive fluid, and inlet and exhaust valves controlling said ports and carried respectively wholly by said upper and 25 lower sections.

2. A pneumatic pump comprising a vertical cylinder, a head member therefor comprising upper and lower separable sections, inlet and exhaust pipes for motive fluid 30 connected with said upper section, said sections having registering passageways formed therethrough extending from said pipes to the interior of the cylinder, an inlet valve controlling one of said passageways, and an 35 exhaust valve controlling the other of said passageways, said exhaust valve being carried wholly by said lower section.

3. A pneumatic pump comprising a cylinder, a head member closing the end thereof, said member being formed with inlet and exhaust ports for motive fluid, inlet and exhaust valves respectively controlling said ports and a motor for actuating said exhaust valve, said motor being carried wholly by 45 said head member, and bodily removable as a unit, without disconnecting said head member.

4. A pneumatic pump comprising a cylinder, a head member closing the end thereof, said member being in the shape of a cylindrical block of substantially uniform diameter throughout, and being formed with inlet and exhaust ports for motive fluid, inlet and exhaust valves respectively controlling said ports, and a motor for actuating 55 said exhaust valve, said motor being enclosed and concealed within said head member.

5. A pneumatic pump comprising a cylinder, a head member therefor having a pocket with an open outer end, and also being formed with ports for the inlet and exhaust of motive fluid, inlet and exhaust valves controlling said ports, an exhaust valve operating motor mounted in said pocket, a

removable cap fitted upon said head member and closing said pocket, and inlet and exhaust pipes for motive fluid connected directly to said cap and communicating with the respective ports.

6. A pneumatic pump comprising a cylinder, a head member therefor having a pocket with an open outer end, and also being formed with ports for the inlet and exhaust of motive fluid, inlet and exhaust valves controlling said ports, a cage carried by said head member inside the cylinder, said exhaust valve being confined within said cage, and an exhaust valve operating motor mounted in said pocket, and having a part projectable into said cage.

7. A pneumatic pump comprising a cylinder, a head member therefor having a pocket with an open outer end, and also being formed with ports for the inlet and exhaust of motive fluid, inlet and exhaust valves controlling said ports, a removable member having an opening and provided with seat for said exhaust valve, said member being carried by said head member with the seat located inside said cylinder, and an exhaust valve operating motor mounted in said pocket and having a part positioned to extend through said opening.

8. A pneumatic pump comprising a cylinder, a head member closing the end thereof, a motive fluid exhaust valve of the float type carried by said head member within the cylinder and removable outwardly therefrom without disconnecting said head member and cylinder.

9. A pneumatic pump comprising a cylinder, a head member closing the end thereof, a motive fluid exhaust valve carried by said head member within the cylinder, and opening inwardly against the existing pressure, and motive means for opening said valve, said valve being removable outwardly without separating said head member and cylinder.

10. A pneumatic pump comprising a cylinder, a head member closing the end thereof, and having an opening therein, a motive fluid exhaust valve, and a valve seat, therefor, both being located inside the cylinder, and an exhaust valve operating motor mounted within said opening, all of said parts being removable outwardly through said opening.

11. A pneumatic pump comprising a vertical cylinder having a head member at its upper end, said head member having a vertical opening therethrough, a valve seat member located at the bottom of said opening, a motive fluid exhaust valve cooperating with said seat member, and an exhaust valve operating motor superposed on said valve seat member and located in said opening, said seat member and motor being removable upwardly through said opening.

12. A pneumatic pump comprising a vertical cylinder having a head member at its upper end, said head member having ports for the admission and exhaust of motive fluid, a free floating exhaust valve actuated directly by the buoyant effect of liquid entering the cylinder, and a cage for said valve, said valve and cage being carried entirely by said head member.
13. A pneumatic pump comprising a vertical cylinder having a head member at its upper end, said head member having ports for the admission and exhaust of motive fluid, and an exhaust valve for controlling said exhaust port, said valve comprising a floating element, and a cage enclosing said element and rigidly secured to the lower side of said head member.
14. A pneumatic pump comprising a chamber having admission and exhaust passages for motive fluid, a valve for closing said exhaust passage and a motor for opening said valve, said motor comprising a piston and a cylinder, said cylinder having a removable end piece provided with a seat for said valve.
15. A pneumatic pump comprising a chamber one end wall of which is thickened and provided with inlet and exhaust passages for motive fluid, said end wall also having a pocket, an exhaust valve, an exhaust valve operating motor comprising a piston and cylinder mounted in said pocket, said cylinder having an end piece provided with a seat for said exhaust valve, and with a port communicating with said exhaust passage.
16. In a pneumatic pump, the combination with a cylinder having a head, of a motive fluid exhaust valve, a seat for said valve removably carried by said head, and a motor for opening said valve, said motor comprising a fluid pressure actuated device having a plunger the free end of which is arranged to extend through the said seat and engage and shift the valve.
17. In a pneumatic pump, the combination with a cylinder having a head, of a motive fluid exhaust valve, a seat for said valve removably carried by said head, and a motor for opening said valve, said motor comprising a fluid pressure actuated device having a rigid plunger, the free end of which, when the motor operates, is brought into engagement with the valve to push it from its seat.
18. In a pneumatic pump, the combination with a chamber having liquid inlet and outlet passages, and motive fluid admission and exhaust valves, of a fluid pressure motor for operating said exhaust valve, a float, and means controlled thereby for governing the admission of pressure to said motor, said float, when in its lowermost position, being located entirely above the low level water line in said chamber.
19. In a pneumatic pump, the combination with a chamber having liquid inlet and outlet passages, and motive fluid admission and exhaust valves, of a fluid pressure motor for operating said exhaust valve, a float and float controlled means, located permanently and entirely above the low water level point in said chamber, for admitting pressure fluid to said motor when the water level has fallen to such point. 75
20. In a pneumatic pump, the combination with a vertical cylinder having liquid inlet and outlet passages, and motive fluid admission and exhaust valves, of a float located permanently at the top or said cylinder, and means controlled by said float for opening said exhaust valve when the level of the liquid in said cylinder has fallen to a predetermined low point. 80
21. In a pneumatic pump, the combination with a vertical cylinder having the usual check valve at its lower end, of a head member closing the upper end of said cylinder and having air inlet and exhaust ports, a valve for closing said exhaust port, a float controlling the opening of said valve, and a water box in which said float is confined, said water box being secured to and supported wholly by said head member. 85
22. In a pneumatic pump, the combination with a vertical cylinder having the usual check valve at its lower end, of a head member closing the upper end of said cylinder and having air inlet and exhaust ports, a valve for closing said exhaust port, 100 a water box secured to said head member, a float in said water box controlling the opening of said valve, and a drop pipe extending downwardly from the bottom of said box to a point adjacent the lower end of said cylinder. 105
23. In a pneumatic pump, the combination with a vertical cylinder having the usual check valve at its lower end, of a head member closing the upper end of said cylinder and having air inlet and exhaust ports, a valve for closing said exhaust port, 110 a motor for unseating said valve, a float controlling the admission of pressure fluid to said motor, and a water box in which said float is confined, said motor and water box being both carried wholly by said head member. 115
24. In a pneumatic pump, the combination with a vertical cylinder having the usual check valve at its lower end, of a head closing the upper end of said cylinder and having air inlet and exhaust ports, a valve for closing said exhaust port, a float controlling the opening of said valve, means 120 whereby said float is lifted to its upper position only when liquid has substantially filled the cylinder, and means whereby said float is maintained by the liquid in its elevated position while the liquid is being ex- 125 130

elled from said cylinder, and is permitted to fall, and cause the opening of said exhaust valve, only when the level of the liquid has reached a point adjacent the 5 lower end of said cylinder.

25. In a pneumatic pump, the combination with a vertical cylinder having the usual check valve at its lower end, of a head member closing the upper end of said 10 cylinder and having air inlet and exhaust ports, a valve for closing said exhaust port, a float controlling the opening of said valve, said float becoming immersed and thus 15 lifted to its elevated position only when the liquid has filled the cylinder, means for maintaining said float immersed and buoyed up by the liquid while liquid is being expelled from said cylinder, and means for withdrawing the liquid from 20 around said float and permitting it to fall and open the exhaust valve only when the level of the liquid has reached a point adjacent the lower end of said cylinder.

26. In a pneumatic pump, the combination with a vertical cylinder having the usual check valve at its lower end, of a head member closing the upper end of said cylinder and having air inlet and exhaust ports, a valve for closing said exhaust port, a vertical conduit in said cylinder having an open 25 lower end, whereby liquid enters said conduit as the liquid fills the cylinder, means for automatically sealing the upper end of the conduit when it has become full of 30 liquid, the lower end of the conduit being also sealed by the liquid, whereby a column of liquid is maintained in the conduit as the liquid is expelled from the cylinder, and is 35 released when the liquid level falls to such a point as to uncover or break the seal at the lower end of said conduit, and means 40 controlled by the release of such liquid column for opening said exhaust valve.

27. A pneumatic pump comprising a chamber having liquid inlet and discharge 45 passages, and motive fluid admission and exhaust valves, a vertically movable float controlling said exhaust valve, and means whereby accumulation of pressure in said 50 chamber causes the liquid to raise said float to its elevated position.

28. A pneumatic pump comprising a chamber having liquid inlet and discharge 55 passages, and motive fluid admission and exhaust valves, a pilot valve controlling said exhaust valve, and liquid level operated means responsive to pressure conditions in said chamber for actuating said pilot valve.

29. A pneumatic pump comprising a chamber having liquid inlet and discharge 60 passages and motive fluid admission and exhaust ports, a valve for closing said exhaust port, a fluid pressure motor for unseating 65 said exhaust valve, means operating, when the liquid has been nearly all ex-

pelled from the chamber, to admit fluid under pressure to said motor, and means whereby the opening of said exhaust valve releases the pressure in said motor.

30. A pneumatic pump comprising a 70 chamber having liquid inlet and discharge passages and motive fluid admission and exhaust ports, a valve for closing said exhaust port, a fluid pressure motor for unseating 75 said exhaust valve, means operating, when the liquid has been nearly all expelled from the chamber, to admit pressure fluid from said chamber to said motor, and means whereby the opening of said exhaust valve 80 serves to vent said motor.

31. In a pneumatic pump, the combination with a vertical cylinder having a check valve at its lower end, and a head member closing the upper end, mechanically independent air inlet and exhaust valves, a 85 liquid discharge pipe and a control pipe extending downwardly into the cylinder from said head member, the lower ends of said pipes being free and permanently open, the liquid discharge pipe projecting below the 90 control pipe, and means operated by the uncovering of the lower end of the control pipe, as the liquid level in the cylinder falls, for opening said exhaust valve.

32. In a pneumatic pump, the combination with a vertical cylinder having a check valve at its lower end, and a head member closing the upper end, air inlet and exhaust valves, independent of each other, a liquid discharge pipe and a control pipe 100 extending downwardly into the cylinder from said head member, and supported wholly thereby, means operated by the lowering of the liquid level in the cylinder to a point beyond the open lower end of said 105 control pipe for opening said exhaust valve, the end of said discharge pipe lying substantially below said lower end of the control pipe, so that it is liquid sealed at all 110 times, whereby entrance of air into said discharge pipe is impossible.

33. A pneumatic pump comprising a cylinder, and a head member closing the end thereof, said head member having a liquid discharge passage formed therein, a liquid discharge pipe carried wholly by said head member and communicating with said passage, said pipe extending into said cylinder, an air admission valve, an air exhaust valve, a cage for the exhaust valve, and an exhaust valve operating motor, all of said parts being also carried wholly by said head member.

34. A pneumatic pump comprising a cylinder, and a head member closing the end thereof, said head member having a liquid discharge passage formed therein, a liquid discharge pipe carried wholly by said head member and communicating with said passage, said pipe extending into said cylinder, 125

an air admission valve, an air exhaust valve, a cage for the exhaust valve, and float actuated means for controlling said exhaust valve, all of said elements being also carried 5 wholly by said head member.

35. A pneumatic pump comprising a cylinder, and a head member closing the end thereof, said head member having a liquid discharge passage, a liquid discharge pipe 10 carried by said head member and communicating with said passage, said pipe extending into said cylinder, an air admission valve, an air exhaust valve, a cage for the exhaust valve, an exhaust valve operating 15 motor, and a float chamber and float for controlling said motor, all of said parts being carried entirely by said head member.

36. In a pneumatic pump, the combination with a vertical cylinder having liquid inlet 20 and outlet passages, and admission and exhaust valves for motive fluid, of a head member closing the upper end of said cylinder and having a vertical opening extending therethrough, and a float controlling the unseating of said exhaust valve, said float being located within said opening and removable upwardly therefrom.

37. In a pneumatic pump, the combination with a vertical cylinder having a liquid inlet 30 at its lower end, of a head member closing the upper end of said cylinder, and having air admission and exhaust ports and a liquid discharge passageway formed therein, said head member comprising separable 35 upper and lower sections, an exhaust valve governing said exhaust port, and a float controlling said exhaust valve, said valve and float being carried by said lower section and removable upwardly therefrom 40 when the said upper section is separated from the lower.

38. In a pneumatic pump, the combination with a vertical cylinder having a liquid inlet 45 at its lower end, of a head member closing the upper end of said cylinder and having air admission and exhaust ports and a liquid discharge passageway formed therein, said head member comprising upper and lower separable sections, said discharge 50 passageway being formed partly in both sections, and a check valve in said passageway located at the junction of the two sections, and removable when said sections are separated.

39. In a pneumatic pump, the combination with a vertical cylinder having a liquid inlet 55 at its lower end, of a head member closing the upper end of said cylinder and having air admission and exhaust ports and a liquid discharge passageway formed therein, said head member comprising upper and lower separable sections, an exhaust valve, an exhaust valve operating motor, and a float controlling said motor, said motor and a float being mounted in said lower section, 60

and removable upwardly therefrom when said sections are separated.

40. In a pneumatic pump, the combination with a vertical cylinder having a liquid inlet at its lower end, of a head member 70 closing the upper end of said cylinder and having air admission and exhaust ports and a liquid discharge passageway formed therein, said head member comprising upper and lower separable sections, air supply 75 and exhaust pipes and a water delivery pipe secured to said upper section and communicating with the respective ports and passageway, and an exhaust valve and controlling mechanism therefor carried by said lower section, said exhaust valve cooperating with 80 said exhaust port.

41. In a pneumatic pump, the combination with a vertical cylinder having liquid inlet and outlet passages, of a head member closing the upper end of said cylinder, and comprising upper and lower separable sections, said upper section having air admission and exhaust ports and control ports and 85 passages formed therein, air supply and exhaust pipes secured to said upper section and communicating respectively with the admission and exhaust ports, an exhaust valve for closing said exhaust ports, and exhaust valve controlling mechanism removably 90 mounted in said lower section and positioned to register with said control ports when the two sections are assembled.

42. In a pneumatic pump, the combination with a vertical cylinder having liquid inlet 100 and outlet passages, of a head member closing the upper end of said cylinder, and having air admission and exhaust ports formed therein, said head member comprising upper and lower separable sections, said upper section having also a control port and a valve seat communicating therewith, and a valve member carried by said lower section and cooperating with said valve seat when the parts are assembled.

43. In a pneumatic pump, the combination with vertical cylinder having air supply and exhaust ports at its upper end, and a liquid discharge passage, of a check valve at the lower end of said cylinder, said check valve comprising a cage member, an annular seat member, an annular retaining member for the seat member, and a disc valve member movable freely within the cage member.

44. In a pneumatic pump, the combination with vertical cylinder having air supply and exhaust ports at its upper end, and a liquid discharge passage, of a check valve at the lower end of said cylinder, said check valve comprising a cage member in engagement 120 with the walls of the cylinder, an annular outwardly removable retaining member below said cage member, an annular seat member held between said cage member and retaining member, and a disc valve member 125 130

resting upon the said seat members within the cage.

45. A pneumatic pump comprising a vertical cylinder, a check valve at the lower end and a head structure closing the upper end thereof, a liquid discharge pipe carried wholly by said head and extending down into said cylinder, an air admission valve, an air exhaust valve, an exhaust valve operating motor, and a float for controlling said motor, all of said parts being carried and supported entirely by said cylinder head structure and either within the same or wholly inside the cylinder.

46. A pneumatic pump comprising a vertical cylinder having a liquid inlet at its lower end and a head closing its upper end, said head having air inlet and water discharge passages extending therethrough, and a cylindrical chamber communicating at its lower end with the interior of the pump cylinder, an exhaust valve, and an exhaust valve operating motor comprising a piston vertically reciprocable within said chamber, the wall of said chamber, at a point below the travel of said piston, being formed with an exhaust port communicating with atmosphere.

47. A pneumatic pump comprising a cyl-

inder having a liquid inlet and a liquid outlet, and a head closing its upper end, said head having air inlet and exhaust passages and a cylindrical chamber, an exhaust valve at the lower end of said chamber, an exhaust valve operating motor comprising a piston vertically reciprocable within said chamber, means for admitting fluid pressure above said piston to actuate the same, and means establishing communication through the piston rod between the space above said piston and the interior of the pump cylinder.

48. In a pneumatic pump, the combination with a vertical cylinder having a liquid inlet at its lower end, of a head closing the upper end of said cylinder and having air admission and exhaust and liquid discharge passageways extending therethrough, an exhaust valve governing said exhaust passageway, and an exhaust valve operating motor comprising a cylinder and piston, said head adjacent said motor being formed of upper and lower separable sections and having therein a chamber in which said cylinder is enclosed and from which it may be removed upwardly.

In testimony whereof I affix my signature.

JOHN L. LATTA.
